UNITED STATES PATENT OFFICE.

HENRY H. ELWELL, OF SOUTH NORWALK, CONNECTICUT.

IMPROVEMENT IN LOCKS.

Specification forming part of Letters Patent No. 37,390, dated January 13, 1863.

To all whom it may concern:

Be it known that I, HENRY H. ELWELL, of South Norwalk, in the county of Fairfield and State of Connecticut, have invented a new and useful Improvement in Horizontal Locks; and I do hereby declare that the following is a full, clear, and exact description of the same, reference being had to the accompanying drawings, making a part of this specification, in which—

Figure 1 is an internal view of my invention, the back plate of the case being removed. Fig. 2 is also an internal view of the same in a reversed or inverted position to that shown in Fig. 1; Fig. 3, a detached view of the bolt and plate pertaining to the same.

Similar letters of reference indicate corresponding parts in the several figures.

This invention consists in constructing the lock in such a manner that it may be inverted and applied to either a right or a left hand door, and admit of the key being inserted into the lock in a proper position—that is to say, bit downward in either position of the lock.

The invention is designed to supersede the "Janus-faced locks," so-called, which are provided with two finished sides and a reversible bolt, or a double-beveled one, and one comparatively expensive to manufacture.

To enable those skilled in the art to fully understand and construct my invention, I will proceed to describe it.

A represents the case of a horizontal lock constructed in the usual way, and B is the latch-bolt, fitted and arranged in the case in the ordinary manner so as to be turned by a knob.

C represents the bolt of the lock, which is formed at one end of the plate D, the latter being much thinner than the bolt, but considerably wider, and having an opening, E, made in or through it, the shape or form of which is clearly shown in Figs. 1 and 2. This opening E has one part, a, much wider than the other part, b, the latter being solely to admit of a projection or bearing, c, which is attached to the inner side of the front plate of the case, passing through the plate D, and without interfering with the movement of the bolt C and plate D. The part b of the opening E has parallel upper and lower edges, and the upper and lower edges of the part a of said opening are of curved form, as shown at d, and are the sur-

faces against which the bit of the key acts in operating the bolt. The upper and lower edges of the part a of the opening E are precisely similar in form, as will be seen by referring to Fig. 3.

F is the key-hole, which is made in the front plate, e, of the lock. This key-hole is of such a form that it will admit the key in proper position, bit downward, in either position of the lock—that is to say, when the lock is so placed as to have its latch-bolt B uppermost, or when inverted so that the bolt C will be uppermost. This result is attained by having both ends of the key-hole made in circular form, as shown at a', to admit of the shank of the key passing through.

G represents the key, f the bit, and g the shank or arbor of the same.

H H represent two tumblers, which are of right-angular form, and fitted at their angles on pivots or pins h h, one at each side of the plate D. The short arms i i of the tumblers H H are connected in consequence of the end of one arm being provided with a lip or projection, j, which fits in a recess, k, in the end of the opposite arm, as shown clearly in Figs. 1 and 2. The longer arms, l l, of the tumblers are provided each with a shoulder, m, near their ends, and have also a notch, n, made in their inner edges just back of the shoulders, as shown in the above-mentioned figures. The ends of the arms i i are also each provided with a short lip, o, and these lips are fitted in one end of a spiral spring, I, the opposite end of which bears against the projection c, previously referred to. On the inner end of the plate D, at each side of it, there is a projection, p, against which the shoulders m m of the tumblers H H bear when the bolt C is within the case A, and said projections, when the bolt C is shoved outward, are within the notches n n of the tumblers. The spring I has a tendency to keep the tumblers H in contact with the projections p p, and it will be seen that said projections and tumblers retain the bolt C in both its inward and outward position, and it will also be seen that, in order to move the bolt C either in or out, the tumblers H must be forced outward free from the projections p p. This result is attained by the bit f of the key G, which, as the key is turned, first acts against the tumblers H H, and throws them out free from the projections p p, and then acts

against one of the curved edges *d* of the part *b* of the opening, and throws the bolt out or in, according to the direction in which the key is turned. In consequence of this arrangement of the plate *D* and tumblers *H*, in connection with the key-hole *F*, it will be seen that the lock may be applied to either a right or a left hand door, and the key *G* in either case inserted in the lock in a proper position, or bit downward—a result not attained by the ordinary locks when inverted; and as the lock represented is technically termed a horizontal one on account of the knob and key-hole being in a horizontal line, the lock will have the

same appearance whether placed on a right or a left hand door.

Having thus described my invention, what I claim as new, and desire to secure by Letters Patent, is—

The plate *D*, with bolt *C* attached, and provided with the opening *E*, in connection with the tumblers *H* and key-hole *F*, arranged substantially as and for the purpose herein set forth.

HENRY H. ELWELL.
